UNITED STATES PATENT OFFICE.

JAMES N. MACRAE, OF STAMFORD, CONNECTICUT, ASSIGNOR TO PETROLEUM HEAT AND POWER COMPANY, OF NEW YORK, N. Y., A CORPORATION OF DELAWARE.

OIL BURNER.

Application filed September 2, 1927. Serial No. 217,043.

This invention relates to an improvement in oil burners of the type known as mechanical burners as distinguished from burners of the centrifugal or rotary type in which a 5 rotating cup is employed for atomizing the fuel, and has for one of its objects the provision of an oil burner of the mechanical type in which carbonizing of oil in the same is eliminated or reduced to a point where no 10 longer detrimental to the operation of the apparatus.

In the type of burner to which the present invention relates, it is customary to provide a burner body on the discharge end of which 15 is mounted a cap through which the oil is discharged in a finely atomized condition. Such burners are inherently unsatisfactory for the reason that when the burner is shut off—not operating—the oil remaining in the 20 burner becomes carbonized due to the heat radiating from the furnace to which the burner is applied and blocks or plugs the oil passages so as to render the burner inoperative.

25 A further object of my invention is to provide a burner of the type above briefly outlined which will be self-draining so that all oil remaining in the burner head when the burner is shut off will be drained back 30 toward the supply to eliminate all possibility of carbonization of the residue oils and blocking of the oil passages. In further explanation it might be said that in oil burning apparatus of the type to which this invention relates oil is supplied from a feed tank which is under a few ounces of pressure. When oil is to be fed to the burner 35 the feed tank is vented to permit the pressure therein to drop to atmospheric and the flow of oil to the burner to cease.

40 In the accompanying drawings I have illustrated one embodiment of my invention,

Fig. 1 showing the same in part sectional elevation;

45 Fig. 2 being a section on the line 2—2 of Fig. 1;

Fig. 3 being a section on the line 3—3 of Fig. 1; and

Fig. 4 being an end view of the burner plunger.

Referring to the drawings in detail, 1 designates the burner body which it will be seen is mounted at an incline to the horizontal. 2 designates the burner body coupling adapted to be connected to a source of oil

under pressure, while 3 designates a strainer and 4 a strainer body nut.

Oil under pressure is supplied to the burner body 1 through the opening 5 in the burner body coupling 2, as will be understood, passes through the strainer screen 6 and is forced along the burner body 1 through the passage 7 extending longitudinally thereof.

The outer end of the burner body 1—that is to say, the end at which ignition takes place, is recessed centrally as indicated at 8, this recess receiving a spring cup 9 removably mounted therein. The rear end or bottom of the spring cup 9 is perforated as 70 indicated at 10 for the passage of oil into the cup.

The spring cup 9 receives a solid fluted plunger 11 bored longitudinally to provide a port 12 extending throughout only a portion of the length of the plunger, intersected by a lateral bore 13 in the plunger so that some of the oil entering the spring cup 9 through the openings 10 therein may be forced through the central port 12 and 80 thence laterally through the bore 13 to work along the outside of the plunger to the end thereof where it enters slots 14 cut transversely across the outer end of the plunger as indicated in Fig. 4.

85 The outer end 15 of the burner body 1 surrounding the recess 8 is screw threaded as indicated at 16 and receives a burner cap 17 which is provided with a bore 18 through which the oil is forced in the operation of the burner as will be understood. It is desirable to maintain the outer end of the plunger 11 in firm contact with the burner cap 17 and to this end a coil spring 19 is provided within the spring cup 9 between the bottom of the cup and the inner end of the plunger.

The outer end of the burner body and the parts just described carried thereby constitute a burner head.

100 The exterior of the plunger 11 is fluted as indicated at 20 in Fig. 3 and in Fig. 4 these flutings extend longitudinally of the plunger.

In operation, oil under pressure is forced along the port 7 in the burner body 1 entering the ports or orifices 10 in the bottom of the spring cup 9, travelling through this cup and along between the flutings 20 at the exterior of the plunger 11 and through the port 12 in the central part of the plunger

until it reaches the outer end of the plunger. The oil then passes along the slots 14 in the outer face or end of the plunger to the center thereof to finally discharge in a fine atomized condition through the burner cap 17.

When the burner ceases operation, the oil remaining in the head will drain back out of the head by gravity, toward the source of supply along the outside of plunger 11 and through the central port 12 therein and out through the orifices 10 in the spring cup 9 to the passage or port 7 in the main body 1 of the burner and hence the entire head of the burner will be freed of oil, and all danger of carbonizing of oil therein and hence blocking of the small passages or holes therein, due to heat radiating from the furnace, is eliminated.

It is to be understood that changes may be made in the construction above described within the purview of my invention.

What I claim is:

An oil burner of the mechanical type, comprising a stationary burner body, a cup

mounted in the outer end thereof, the cup facing the outer end of the burner body and having its bottom perforated adjoining the wall of the cup, a spring plunger mounted in said cup, said plunger being provided internally with a longitudinally extending oil passage way and with a transverse oil passage way intercepting the said longitudinal passage way, and externally with longitudinally extending oil passage ways communicating with the cup and with said transverse oil passage way, a burner cap secured to the extreme end of the burner body and engaging the spring plunger to retain the same in place in the said cup, said plunger being provided with passage ways across the end thereof for permitting of the flow of oil between the outer end of the plunger and said cap, said cap being provided with an oil passage way whereby oil passing along the end of the plunger may be discharged through said cap.

This specification signed this 29th day of August, 1927.

JAMES N. MACRAE.
